UNITED STATES PATENT OFFICE

2,467,631

MACHINE FOR MAKING CONCRETE PIPE

Laurie F. Parker, Minden, La.

Application February 14, 1947, Serial No. 728,693

1 Claim. (Cl. 25—36)

1

The object of the present invention is to provide a compact machine for simultaneously forming a plurality of lengths of concrete pipe, in such manner that whilst the finished pipe is being removed from the molds, as to two or more of the latter, the remainder may be in the process of filling and forming operations. The machine is characterized by a provision of reciprocating and rotary forming heads, which act within the molds to compress the concrete mixture and to define the interior cavity of the pipe.

The invention will be described with reference to the accompanying drawings, in which:

Fig. 1 is a view in elevation, showing an embodiment of the invention, the driving motor not being shown and the forming disks being raised to the position they will assume after an active operation with respect to two of the molds;

Fig. 2 is a view similar to Fig. 1 showing the position of the elements when the forming heads are at their lowermost positions;

Fig. 3 is an enlarged view in elevation, partly broken away to show the forming heads and their driving mechanism preliminary to active strokes and rotation of the forming heads;

Fig. 4 is a schematic plan view partly broken away, showing the motor and drive belt, the shafts and drive gearing for the forming heads, and the gear housing, certain spacer rods being broken away on the line 4—4, Fig. 1;

Fig. 5 is a horizontal section on the line 5—5, Fig. 1;

Fig. 6 is a sectional elevation taken longitudinally of one of the molds showing one of the forming heads near the end of an active stroke and showing certain supporting elements for the molds; and

Fig. 7 is a top plan view of one the molds.

Fig. 8 is a perspective view of the completed concrete tube as produced by the apparatus;

Fig. 9 is a horizontal section through one of the molds centrally thereof and through one of the forming head shafts to illustrate the action of the latter on the concrete mixture which also is shown in section.

Referring to the drawings, the machine consists of a base 1 from which rises the tubular standard 2. Mounted for rotation on the standard is a mold table 3 which has an overlying member 3x. The member 3x has, for clarity of illustration, been slightly raised in Figs. 2 and 3, but in practice this member will rest upon member 3. Its purpose is to provide a series of forming head receiving passageways at 4, Fig. 3, and like passageways 4x are formed in the table 3.

2

On top of the table member 3x at the rear and at the sides of each passageway 4 there may be provided registration abutment lugs 5 for the molds 6 and like lugs may be carried by a top plate 7 which may support a pan 8. The plate 7 and pan 8 will be provided with apertures for the upward passage therethrough of the formers 9, and the top plate and table 3 are held in spaced relationship by spacer rods 17.

Each mold consists of two semi-cylindrical halves 6 hinged at 11 and having handles 12. It is preferred that a latch 13 be pivoted to the shaft 14 of one of the handles, the latch having a notch at 13x, Fig. 7, to engage shaft 14x of the other handle. As indicated in Fig. 1 and also Fig. 2, the latch may have two spaced arms 13 connected by their own handle member 13xx. It is also preferred that the mold member 6 be formed with internal horizontal channelways 6x to provide ribs on the exterior of the formed pipe. The purpose is not pipe reinforcement alone, the primary function being to restrain the upward movement of the concrete pipe in the process of its formation by the upward and rotational force of the forming heads.

The table members, the molds carried thereby, with the cover plate 7 and pan 8 are rotatable upon standard 2 when the forming heads 9 are raised. The table support may be upon a collar 2x carried by the standard 2.

Above the pan 8, standard 2 carries a collar 14 which supports a gear box 15. Passing through this gear box are two shafts 16, each of which carries one of the forming heads 9. Except at a point always above the gear box each shaft 16 is provided with a long keyway 15x, and each shaft has keyed thereto, by means of said keyway and a key, a driven gear 18 in mesh with a drive gear 19, the latter being on a shaft 20 supported toward its lower end by a bearing boss 21 at the top of the gear box, thence rising through a boss 22 carried by a plate 23 and thence carrying a pulley 24 which receives a belt 25 leading to the drive pulley of a motor 26, Fig. 4. Plate 23 is tied to the gear box by spacer rods 27.

Each forming head shaft 16 passes through plate 23 and has a threaded upper area in the threaded wall of a fixed boss 23x carried by said plate 23. Therefore, as the motor and gearing rotate the two forming head shafts 16 they have endwise movements accordingly. The motor is of reversible type to give downward and upward movements to the forming head shafts.

Plate 23 is connected by tie rods 28 with a plate

29 and the upper ends of shafts 16 carry a bar 30 which is slidably mounted on tie rods 28. Vertical cushioning rods 31 pass through plates 23 and 29. The spacer rods 28 and the cushioning rods 31 are provided with a series of springs for cushioning effect. Thus, when the shafts approach their lowermost position, plate 30 engages rings slidably mounted on the spacer rods 28 and above springs 33 so that in the continued downward movement of shaft 16 and the forming heads, the springs are compressed. Thus quick downward movements of the forming heads are cushioned. Toward the end of the final upward movement of shaft 16, plate 20 strikes springs 34 on the spacer rods 28 for cushioning effect. Plate 30 also strikes a fixed collar 31x on the lefthand cushioning rod 31 and moves that rod upwardly to compress a spring 35. Also, at the end of the downward movement of the shaft 16 the plate 30 may engage a fixed collar 31xx on the righthand cushioning rod 31, moving said cushioning rod downwardly in compression of a spring 36 thereon.

In the operation of the machine, shaft 16 may be rotated until the tops of the forming heads 9 are at the bottom or approximately the bottom of the two molds 6, the latter being closed and latched. A cement mixture with the minimum moisture required for bonding of its elements is then placed in each mold through the open upper end of the pan 8, as for example to the level indicated at 1, Figure 3. The machine is then put in operation to cause the forming heads to rotate and rise upwardly. The forming heads are of specific design as shown more particularly in Figures 3 and 9. Each head is formed with a cam-like cavity having a pressing shoulder at 9x. As shown in Figure 9, the cement C passes into the cavity and against the shoulder so that in the rapid rotation and upward movement of each forming head, the shoulder acts with positive pressure and also with centrifugal action to compress the cement between the forming head and the mold wall, and with high pressure. The moisture content of the cement being very low, this action of the forming heads enables removal of the formed pipe immediately after the forming heads withdraw from the tops of the molds.

During this forming action two of the molds may be in the process of removal and their

formed pipe sections and two of the molds may receive fresh charges of cement. It will be understood that when a pipe forming operation has been concluded, the parts being in the position of Figure 1, the mold table may be rotated to bring two fresh charge molds into registration with the two forming heads. Means for automatically stopping the motor 26 when the forming heads reach their uppermost position may be provided, and with or without such means a hand control switch such as that indicated at 37 may be provided. It also will be understood that foot or hand registration means may be provided for the mold table so that when the same has been rotated it may be latched to exact operative position with respect to two freshly charged molds and the overlying forming heads 9.

It will be understood that various modifications may be made in the form and arrangement of the elements constituting the embodiment herein illustrated, without departing from the spirit of the invention.

What I claim and desire to secure by Letters Patent, being as follows:

25 In a machine for making concrete pipe, consisting of a standard, a table support rotatable on the standard, a gear box above the said table support, a plurality of shafts extending through the gear box, forming heads on said shafts, gearing in said box adapted for rotating said shafts, 30 guide rods arranged in parallelism with the shafts above the mold supporting table, a cross-head carried by the shafts and received on said guide rods, and cushioning means carried by said 35 guide rods above and below said crosshead.
